UNITED STATES PATENT OFFICE.

JOHN L. P. SPOONER, OF PROVIDENCE, RHODE ISLAND.

MOLD.

SPECIFICATION forming part of Letters Patent No. 443,389, dated December 23, 1890.

Application filed May 31, 1890. Serial No. 353,785. (No model.)

To all whom it may concern:

Be it known that I, JOHN L. P. SPOONER, of Providence, in the county of Providence and State of Rhode Island, have invented certain new and useful Improvements in Molds and Method of Making Same, of which the following is a full, clear, and exact description.

This invention consists of a mold constructed substantially as hereinafter fully described, for the manufacture more particularly of seamless hollow or solid plated ingots—such, for instance, as are described and shown in Letters Patent of the United States issued to me, dated January 7, 1890, and numbered 419,085; and the invention also consists of the method of making such mold, all substantially as hereinafter fully described, reference being had to the accompanying sheets of drawings, in which is illustrated a mold constructed in accordance with this invention, and the method of making the same.

Figure 1 is a vertical central section of the mold in two parts. Figs. 2, 3, and 4 are cross-sections on lines 2 2, 3 3, and 4 4, respectively, of Fig. 1. Figs. 5 and 6 are vertical central sections showing the manner of making the mold shown in Fig. 1. Fig. 7 is a cross-section on line 7 7, Fig. 5. Fig. 8 is a cross-section on same line as Fig. 7, but with the parts turned one-quarter round. Fig. 9 is a cross-section on line 9 9, Fig. 5; and Fig. 10 shows a vertical central section, to be herein-after referred to. Fig. 11 is a detail section of the lower end of Fig. 5.

In the drawings, A represents the mold made in two parts B and C, the part B being in the shape of a cylinder having a vertical central chamber D, open at its upper end, and a bottom E, the chamber being of two diameters, the portion F being of larger diameter than the portion G, the other part C of the mold being of tube form and open from end to end and adapted by its external diameter to fit in the upper chamber F of the part B and held in place by a shoulder a, resting on its upper end, the two parts being made of a fire-resisting material, such as clay and plum-bago mixed with water, and molded into the proper shape when in a moist condition, as will now be described.

In Figs. 5 to 10 is shown the manner of making the mold, and in these figures H is

a shell or casing of cast-iron, having a central vertical opening or chamber b through it from end to end, its internal diameter and shape being the same as the external diameter and shape required for the mold. This shell or casing is square in cross-section on the outside, and over its upper end fits a cap or cover J, also made of cast-iron, and when in place it is secured by screws d, passing through its sides and screwing into the shell. The cap or cover extends up in neck form K to a desired height and has a central vertical passage f through it, which when the cap is in place is vertically central over the chamber D of the shell.

Adapted to closely fit in the passage or opening f of the cap, but so that it can be moved up and down therein, is a tube L of steel, having secured within it another tube M of steel, which extends below the tube L a certain distance required in the manufacture of the mold, and when placed in the cap-passage f and moved down into the chamber D of the shell, the lower end g of the tube M should stop a short distance from the bottom of the shell according to the thickness desired for the bottom E of the part B of the mold, and when at the proper place the lower end h of the tube L rests upon a cross plug or bar N, disposed in a transverse opening m in the shell, of the same thickness as the diameter of the tube L and of a width desired, the plug having an opening n through its width for the tube M to pass through it. The distance the tube M projects below the lower end h of the tube L is regulated by the height of the cross-bar from the bottom of the shell to give the desired thickness of the bottom of the part B of the mold. These tubes L and M make the core for the shell, and in these views are shown as made in two parts, because it is easier to make them; but the two can be made as one having the two diameters and a shoulder h, or the two can be connected together, as shown in Fig. 10, the tube L having the tube M screwed into it at its lower end and a portion r screwed into its upper end to form a handle, or this portion may be dispensed with.

Within the tube or core M is a small rod or wire P, of iron, long enough to extend down through the tube, to screw by its lower end into a passage t in the bottom of the tube, to close and open such passage when desired.

In the lower end of the chamber of the shell is a block Q, closely fitting in the same, but so it can slide up and down therein, and resting on a plate R, adapted to slide across the end of the shell in a dovetail groove u, and having an opening S through it.

In the preparation of the part B of the mold the block Q is inserted in the bottom of the chamber and the plate R slid into its place, 10 forming a bottom for the chamber and holding the block in place, and the cap secured in place over the end of the shell by its screws. The fire-resisting material, consisting of plumbago and clay, is then in any suitable 15 portions mixed with water, and when in a moist and plastic condition a sufficient quantity to make the mold is put into the shell at its upper end and the core-tube inserted in the passage f in the cap and pressed down 20 firmly into the plastic material until the tube L rests by its end h on the cross-plug N, the lower portion M having passed through the opening n in the plug down nearly to the block or false bottom Q, according to the 25 thickness desired for the bottom of the mold. The whole is then allowed to stand until the fire-resisting material is sufficiently set and hard, and then the wire or rod P is removed from the core-tube M, leaving the opening t 30 in the bottom of the core M free for air to pass through it into the chamber of the molded material, when the core-tube is withdrawn, the cap taken off, which leaves the upper end of the shell free for the mold to be removed, 35 which is done by taking any suitable plunger and inserting it in the opening S in the bottom sliding plate R and pressing it firmly up against the block Q, which forces it and the mold up through and out of the shell, it then 40 being left to dry and harden to be afterward baked, as usual, into proper condition for use. The opening t in the bottom of the core-tube after the rod P is removed allows air to enter 45 through the tube into the chamber of the mold below the core-tube as it is withdrawn, equalizing the air-pressure on both sides of the mold and preventing any collapsing of the mold or injury to the same, as would otherwise happen if the core-tube was solid and 50 there was no opportunity for air to reach the space in the mold-chamber below the core as it is being removed.

The operation of making the thimble or sleeve C is substantially the same as making 55 the mold proper, the cast-iron shell being correspondingly shorter, and a solid core being used, dispensing with the hollow one and the rod P, as in making the sleeve, it being quite short, the core can be solid, all of which is 60 shown in Fig. 6.

T is the cast-iron shell, having a central vertical chamber v of a diameter to correspond to the external diameter of the sleeve, and having a recess w in its upper end for 65 the flange or shoulder a to fit therein, and

having a cap to be secured by screws, which can be the same one used for the other part of the mold.

U is a steel rod to fit the passage f in the cap and neck, and V is an extension of the rod of less diameter and of a length to extend down into the chamber v of the casing the required distance, the rod V being of a diameter corresponding to the internal diameter of the sleeve being molded. The shell also has 75 a block W to fit its chamber, having a central depression y for the lower end of the rod V to rest therein, and a transverse sliding plate R, fitting in a dovetail groove u, for the block to rest on, and having an opening S 80 through it.

In making the sleeve the block W and sliding plate R are put in place and the prepared moist and plastic material or fire-resisting material placed in the chamber of the 85 shell of the quantity desired. Then the cap is put in place and secured by its screws, the rod U inserted in the neck of the cap and pressed down through the same until its extension V rests in the depression y in the 90 block, which brings the lower end of the part U of the rod just at the top of the casing, pressing the fire-resisting material into its place round and about the core and into the recess w in the shell, and when it is sufficiently 95 dry and set, the rod is taken out, the cap removed, and any suitable plunger or rod is inserted in the opening S in the sliding plate and pressed up firmly against the block W, which forces the block and molded sleeve up 100 through and out of the shell, which, being allowed to dry and harden, is baked in the usual manner.

The manufacture of seamless plated ingots from a mold having a thimble is described 105 and shown in the Letters Patent referred to, and therefore there is no need of describing the same in this application, except to state that the thimble in this application is for the purpose of guiding the core in the mold when casting the ingot, its internal diameter being the diameter of the core of the ingot, and the difference between its internal diameter and the diameter of the chamber of the mold being the thickness of the plating on the ingot. 110 The shell or casing and its parts connected therewith can be made of any suitable material, but the material stated is practical and satisfactory in its results; also, the outside of the shell can be made of any suitable 115 shape desired; also, the mold can be made of any suitable fire-resisting material or materials.

This mold is applicable for molding other articles as well as seamless plated ingots. 125

Having thus described my invention, what I claim is—

1. A mold for casting seamless plated ingots or other articles, consisting of a shell or casing of fire-resisting material and a thimble 130

or sleeve of fire-resisting material adapted to fit in the upper part of the shell or casing as a guide for the core of the mold.

2. A mold for casting seamless plated ingots or other articles, consisting of a shell or casing of fire-resisting material and a thimble or sleeve having a shoulder on its upper end made of fire-resisting material adapted to fit therein, for the purpose specified.

10 3. The method of making a mold for making seamless plated ingots or other articles, consisting of first placing a fire-resisting material in a suitable chamber or mold, then

pressing and molding it into shape by any suitable plunger or core, then removing a central portion of the core to allow air to enter at the bottom of the chamber of the plastic material as the body portion of the core is being removed.

In testimony whereof I have hereunto set my hand in the presence of two subscribing witnesses.

JOHN L. P. SPOONER.
